UNITED STATES PATENT OFFICE

ADELE W. KEHLER, OF SAN FRANCISCO, CALIFORNIA

DESIGN FOR A COMBINATION TRAY

Application filed January 17, 1930. Serial No. 34,168. Term of patent 7 years.

To all whom it may concern:

Be it known that I, ADELE W. KEHLER, a citizen of the United States of America, residing at San Francisco, in the county of San Francisco and State of California, have invented a new, original, and ornamental Design for Combination Trays, of which the following is a specification, reference being had to the accompanying drawing, forming a part thereof.

The figure is a front perspective of the article, showing my new design.

I claim:—

The ornamental design for a combination tray substantially as shown.

ADELE W. KEHLER.
